MACHINE COMPANY, OF SPRINGFIELD, VERMONT, A CORPORATION OF VERMONT

MEANS FOR CORRECTLY SETTING RELIEVED TAPS IN THREAD-FINISHING MACHINES

Application filed December 6, 1922. Serial No. 605,198.

This invention relates to means and mechanism by which relieved taps may be properly located in a grinding machine or other thread finishing machine so that the tool may properly engage the threads and yet wherein the periodic relative retraction between the tap and the tool may be caused to take place in correct relation to the flutes of the tap without requiring that the flutes be formed in any fixed relation to the threads. For this purpose the angular relation of the flutes and relieving action, which is fixed may be determined and the tap so fixed to its rotational driving mechanism regardless of whether or not the tool properly engages the threads, and then the tap and tool may be adjusted relatively axially of the tap until the tool is properly related to the threads. The tap may then be given its rotating and traversing motion relative to the tool in the usual manner with full assurance that the threads will be correctly finished and that the relief will be properly related angularly to the flutes.

In order to carry out this method the work and tool-carrying mechanism of the finishing machine are relatively adjustable axially of the work independently of their relative traversing movement, and in order to insure that this adjustment be correct before the tap is placed in the machine the adjustment is indexed and an indicating device correspondingly indexed is employed for testing each individual tap before it is placed in the machine. The machine index having been set to correspond with the index of the testing device set for any particular tap, the machine is then in proper adjustment to correctly finish the threads of that tap.

40 For a more complete understanding of this invention, together with further objects and advantageous details and combinations of parts, reference may be had to the accompanying drawings in which

45 Figure 1 is a top plan of the testing indicator device by means of which the driving dog is correctly related to the tap for the relieving action and the setting of the finishing machine for proper engagement of the tool with the tap is indicated.

50 Figure 2 is a side elevation of the same.

Figures 3 and 4 are detail sections on lines 3-3 and 4-4, respectively, of Figure 1.

Figure 5 is a fragmentary front elevation partly in section of a grinding machine having an indicator thereon which may be set according to the indication obtained from the testing device and which, when set, insures the correct relation of the grinding wheel to the work.

The finishing machine may be of any suitable type but for the purpose of illustration a grinding machine of the general form illustrated in my Patent No. 1,739,753, issued December 17, 1929, will be taken. 60

In Figure 5 a portion of this machine is shown and will be described sufficiently to illustrate the relation of the testing device thereto and the method of its use. Referring to this figure at 1 is indicated a traversing work carriage slidably supported on a base 2. This work carriage supports live and dead centers 3 and 4 between which the tap, shown at 5, may be supported. At 6 is indicated a grinding wheel having a grinding face shaped to the contour desired between adjacent threads of the tap. The dead center 4 is caused to move the tap laterally relative to the grinding wheel 6 in timed relation to its rotation in order to cause a deeper cut to be made progressively back from the cutting edges of the tap defined by one side of each of the usual flutes, these flutes being indicated at 7. As shown the center 4 is supported in a block 10 having a hemispherical face seated in a disk 11 which is made fast by bolts 12 to a sleeve portion 13 through which the center projects. This center 4 is given a gyratory motion within the sleeve, this motion being effected by means of an

eccentric mounting at its outer end which is driven in time with the rotation of the work by means of change gearing indicated at 14. Details of this mechanism are shown in the patent above referred to and further explanation is believed unnecessary in the present case. The live center 3 carries a face plate 20 through which rotative driving may be imparted to the tap by means of a lathe dog or other suitable element 21.

In order that the grinding wheel may prop- 100

erly follow the threads of the tap it is necessary that the tap and wheel be traversed relatively as the tap rotates. For this purpose the carriage 1 may be traversed by means of an edge cam 25 driven in time with the rotation of the tap which engages a cam roller 26 fixed to a bracket 27 having an operative connection to the carriage 1. The roll 26 is held in contact with the cam 25 in order to impart a return traverse by means of a spring 28 engaging a bracket 29 extending from the carriage at one end and a bolt 30 extending from the base 2 at its other end. As will later more clearly appear it is necessary to provide for adjusting the tap and tool axially of the tap to provide for a proper engagement of the tool with the tap threads of the different taps when the tap is correctly positioned to cause the relieving to take place in proper relation to the flutes. For this purpose the bracket 27 is carried by a shaft 35, being threaded thereon between a pair of brackets 36 and 37, depending from the carriage 1. By rotation of the shaft 35 it is evident that the bracket 27 may be moved relative to the carriage 1 so as to impart a traverse of the carriage relative to the wheel 6 independent of the traverse by means of the cam 25 which is timed with the tap rotation. In order to determine the proper setting of the bracket 27 relative to the carriage the shaft 35 has fixed thereon an indicating wheel or disk 39 having graduations marked thereon with which cooperates a fixed index finger 390 this being in effect a micrometer adjustment. At the outer end of the shaft 35 may be fixed a handle 38 by which it may be rotated.

Referring now to the indicating device for determining the proper setting of the indicator 39 on the machine so that the tap and grinding wheel may be correctly related, this device comprises an entirely separate mechanism from the grinding machine, and which is shown in Figures 1 to 4 inclusive. Referring to these figures, 40 indicates a supporting plate on which are relatively adjustable lengthwise bracket blocks 41 and 42. The bracket 41 may be fixed in adjusted position by means of a stud 43 threaded in the block and passing through a slot 45 longitudinally disposed through the plate 40, and having threaded on its lower end a tightening nut and washer 46. The block 41 has a hole or bore 47 horizontally disposed therein for the slidable reception of a center 48 which has a reduced shank portion 49 extending through a smaller hole 50 concentric with the bore 47 and which forms a guideway for this shank. Seated within the bore 47 and surrounding the shank 49 is a coil spring 51 which reacts between a shoulder 52 formed at the rear end of the bore and a shoulder 53 formed on the center at the end of the reduced portion. This spring normally projects the center to-

ward the block 42 as far as may be permitted by a washer 54 placed thereon and held in position by a pin 55 at the opposite side of the block 41. Adjacent the center 48 an abutment pin 58 is adjustable axially in a perforation 59 parallel with the hole 47. This pin 58 is in position to be engaged by the driving dog 21 which may be clamped to the tap 5 adjacent the end of its shank portion which may be supported by the center 48. The other end of the tap is supported by a center 66, a portion of which is formed threaded as at 67 and engages a mated threaded opening 68 in the block 42, the two centers being in axial alignment. The center 66 outwardly of the threaded portion 67 carries an index wheel 69 graduated in the same manner as the wheel 36 on the grinding machine and with which cooperates an index finger 70. This index finger as shown is fixed to the top of the block 42 by means of a clamping block 71 held in position by a screw 72. The index member 70 also has fixed thereto a stop pin 73 with which cooperates a mating pin 74 extending from the index wheel 69. Outwardly of the index wheel the center 66 has pinned thereto a hand wheel 75 by which it may be rotated, the hand wheel and the indexing disk being preferably clamped in position between a flange 76 on the center and a nut 77 threaded on the reduced extremity 78 of the center and bearing against the outer face of the hand wheel 75. By turning the hand wheel it is evident that the center 66 may be moved axially and the tap carried between this center and the center 48 may be moved therewith, the center 48 being permitted to retract within the block 41 against the pressure of the spring 51 as the center 66 is moved thereto by turning the hand wheel.

Means are provided in this mechanism by which the driving dog 21 may be fixed to the tap 5 in such angular relation to the tap that when the tap with the dog remaining fixed thereto in the same relation are placed in position in the grinding machine where the dog is driven from the face plate thereof, the relieving action accomplished by the gyroscopic motion of the dead center of the machine shall take place properly related angularly to the tap flutes. For this purpose an abutment 80 has a portion 81 engaging within one of the flutes of the tap, this abutment 80 being fixed by means of a screw 82 to a portion 83 projecting from the block 42. This abutment block is so positioned angularly to the abutment pin 58 that when the block 80 engages within one of the flutes of the tap and the driving dog 21 rests against the pin 58, the driving dog may be clamped to the tap in this angular relation, which is the proper angular relation to effect the desired relief of the tap threads in the grinding machine. This having been effected it is then necessary to determine the axial po-

sition of the tap so as to cause the grinding wheel to properly mate the tap threads. For this purpose an element which may accurately engage the tap threads is provided, this comprising a pointed screw 90 threaded in one arm 91 of a frame member 92. This frame member is movable relative to the base 40 so as to permit the screw 90 to be positioned axially of the tap to properly seat its point between adjacent threads and as shown is pivoted on a pin 93 which passes through the lower portion of the member 83 and also through an oppositely disposed lug 94 projecting from the block 42 in spaced relation to the portion 83. The frame 92 has a pair of downwardly extending ears 95 and 96 through which the pin 93 passes. Between the portion 94 and the ear 96 surrounding the pin 93 is positioned a coil spring 97 which acts to normally hold the ear 96 against the portion 83 of the block 42. The pin 93, however, has passed therethrough on the opposite side of the portion 94, a pin 98 which may engage the inner face of the ear 95. By pressing inwardly on the head 99 of the pin 93, the pin 98 may be forced against the ear 95 so as to slide the frame 92 transversely to bring the point of the screw 90 into engagement between adjacent threads of the tap, this screw 90 being so adjusted as to just clear the threads when the frame 92 is in its normally retracted position. Due to the pivotal mounting of this frame, its upper end may move in a direction axially of the tap when the screw 90 is projected into engagement between the threads so that this screw may properly seat itself between these threads. The parts of this mechanism and the grinding machine are so proportioned that when the screw 90 is in a definite location axially, if the indicator 39 on the machine is set to correspond with the indicator 69 on the device the grinding wheel 6 of the machine properly engages the threads of the tap. The device, therefore, is provided with means for ascertaining this correct position of the screw in an accurate manner.

As shown more particularly in Figures 1, 3, and 4 the frame 92 is provided with an upper standing portion 100. Opposite to this portion is positioned the stem 101 of a length measuring instrument of any suitable description indicated at 102. As shown this instrument is the well known Waltham indicator by which movements of the stem 101 toward the indicator casing are correspondingly measured on a dial 103 by a pivoted pointer 104. This instrument is designed to show minute movements of the stem 101 and is extremely accurate, especially where these movements are very short so that the pointer 104 moves a comparatively short distance from its zero point. This indicator is shown as fixed to the block 42 by means of an ear 105 projecting therefrom and through which

passes a fastening screw 106 engaging the block 42. In order to take advantage of the extremely accurate index of the instrument 102 when it registers near the zero mark, the driving dog 21 having been fixed to the tap in proper angular position, the screw 90 is brought into engagement between adjacent threads in such position that the portion 100 is forced against the stem 101, thus moving the pointer 104. By turning the hand wheel 75 the center 66 is moved to carry the tap axially until the pointer 104 reaches its zero position. If now the reading of the indicator wheel 69 be taken and the indicator wheel 36 of the machine be adjusted to the same indication, the grinding machine is properly adjusted so that the grinding wheel may properly engage the threads when the tap is placed in position therein with its driving dog in position to be driven from the grinding wheel face plate and remaining fixed to the tap in the relation determined when the tap was in the indicating device.

While the indicating device might be designed so as to permit the reading on the instrument 102 to be transferred to the dial of the machine, more accurate results are obtained with this particular instrument by adjusting it to zero reading and then taking the indication of the dial 69 for setting the grinding machine.

The method and certain mechanism by which this method may be carried out according to this invention having thus been described, it should be evident to those skilled in the art that many changes and modifications may be made without departing from the spirit or scope of this invention as defined by the appended claims.

I claim:

1. A device of the class described comprising a pair of centers between which a tap may be supported, an abutment adjacent one of said centers against which a driving dog secured to a tap supported on said centers may engage, and indicating means for adjusting said centers and tap axially to bring the threads of said tap in desired positions.

2. A device of the class described comprising a pair of centers between which a tap may be supported, an abutment adjacent one of said centers against which a driving dog secured to a tap supported on said centers may engage, an abutment for engagement within a flute of the tap to position the tap in a proper angular position at which the dog may be fixed to said tap, and indicating means for adjusting said centers and tap axially to bring the threads of said tap in desired positions.

3. A device of the class described comprising a pair of centers between which a tap may be supported, an abutment adjacent one of said centers against which a driving dog secured to a tap supported on said centers

- may engage, an element engageable between adjacent threads of the tap, and indicating means for adjusting said centers and tap axially to bring said element to a predetermined position.
4. A device of the class described comprising a pair of centers between which a tap may be supported, an abutment adjacent one of said centers against which a driving dog secured to a tap supported on said centers may engage, and an abutment for engagement within a flute of the tap to position the tap in a proper angular position at which the dog may be fixed to said tap.
- 10 5. A device of the class described comprising a pair of centers between which a tap may be supported, means to hold a tap held between said centers against rotation with its flutes definitely positioned with respect to rotation about the axis of the tap, and means to adjust said centers with the tap supported thereby axially to bring the treads of said tap in the desired positions.
- 20 6. A device of the class described comprising a pair of centers between which a tap may be supported, means to hold a tap held between said centers against rotation, and means to adjust said centers with the tap supported thereby axially to bring the threads of said tap in desired positions.
- 25 7. A device of the class described comprising means for supporting a tap against rotation with its axis fixed and with the tap in a definite position with respect to rotation about its axis, and means for adjusting certain of said supporting means with the tap supported thereby endwise to bring the threads of the tap in desired positions.
- 30 8. A device of the class described comprising a support, a pair of centers carried by said support and between which a tap may be mounted, a post positioned adjacent one of said centers and against which a driving dog engaging a tap supported on said centers may engage, means carried by said support and engageable within a flute of said tap to hold it in a definite angular position in which position the dog engaging said post may be clamped to the tap, an indicator, and means operatively associated with said indicator for relatively adjusting said indicator and said centers and tap longitudinally of said tap, said indicator being constructed to show the relative adjustment of tool and work holder of a tap finishing machine to properly relate the threads of said tap to the tool of said machine, the tap being rotated in the machine through said dog.
- 35 9. A device of the class described comprising a support, a pair of centers carried by said support and between which a tap may be mounted, a post positioned adjacent one of said centers and against which a driving dog secured to a tap supported on said centers may engage, means carried by said support for engaging in a flute of the tap to determine an angular position of the tap for clamping the driving dog thereto, a frame movable relative to said support, an element carried by said frame and projectable into mating engagement with the threads of the tap, and indicating means for adjusting said centers carrying the tap axially to bring said element to a definite position with respect to the threads of the tap.
- 40 10. A device of the class described comprising a support, a pair of centers carried by said support, one of said centers being axially yieldable from the other center and the other center being axially adjustable toward and from said one center, said centers being adapted to support a tap, a post positioned adjacent said yieldable center and against which a driving dog secured to a tap supported on said centers may rest, a frame movable on said support, an element carried by said frame and projectable into mating engagement with the threads of the tap and movable axially of the tap by movement of said frame, an indicator for showing the position of said element axially of the tap relative to a determined position, and a micrometer indicator for showing the adjusted position of said other center and actuatable to bring said element to said determined position.
- 45 11. A device of the class described comprising means for supporting a tap against rotation about its axis, means including an indicator responsive to the axial position of selected tap threads of the tap so supported, and means for adjusting certain of said supporting means with the tap supported thereby axially of the tap to bring the indicator to a desired indication, said device including means for indicating the adjusted position of said adjusting means.
